UNITED STATES PATENT OFFICE.

SAVERIO CALAUTTI, OF NEW YORK, N. Y.

DESIGN FOR AN AUTOMOBILE-HORN.

41,897.

Specification for Design.

Patented Nov. 7, 1911.

Application filed June 6, 1910. Serial No. 565,414. Term of patent 7 years.

To all whom it may concern:

Be it known that I, SAVERIO CALAUTTI, a subject of the King of Italy, residing at the city of New York, borough of Manhattan, in the county and State of New York, have invented a new, original, and ornamental Design for an Automobile-Horn, of which the following is a specification, reference being had to the accompanying drawings, forming a part thereof, in which—

Figure 1, is a front or face view showing a horn incorporating my said design; Fig. 2, is a bottom view thereof, and Fig. 3, is an end view.

In said drawings, the horn is shown as comprising a body having a flat back, and a spiral-like front of pyramidal form. At its outer portion said spiral body portion gradually increases in width to form a flaring end or horn. The mouth of said flaring

end or horn is elliptical in outline and beveled, and has a slightly concaved cover terminating in a rounded bead or rim which embraces the flaring end or mouth of said horn. The said concaved cover is provided with perforations. A tubular section of comparatively small diameter is arranged upon the back of the body portion of the horn, and has its inner end terminating below the center of the spiral, and has its outer end projecting beyond the edge of said spiral body portion.

I claim:

The ornamental design for an automobile horn, as herein shown and described.

SAVERIO CALAUTTI.
